UNITED STATES PATENT OFFICE.

CARL F. KRESS, JR., OF JOHNSTOWN, PENNSYLVANIA, ASSIGNOR TO THE LORAIN STEEL COMPANY, OF PENNSYLVANIA.

RAILWAY-FROG.

SPECIFICATION forming part of Letters Patent No. 639,251, dated December 19, 1899.

Application filed July 22, 1899. Serial No. 724,852. (No model.)

To all whom it may concern:

Be it known that I, CARL F. KRESS, Jr., of Johnstown, in the county of Cambria and State of Pennsylvania, have invented a new and useful Improvement in Railway-Frogs, of which the following is a full, clear, and exact description, reference being had to the accompanying drawings, which form a part of this specification.

10 My invention relates that class of frogs which are built up of rails or rail-sections properly fitted together and connected by a solid chuck cast between them and through apertures in their web portions.

15 The objects of my invention are to provide a frog of the class described which shall be light and durable and built up of a minimum of parts capable of being readily constructed, fitted, and secured together, and which by its 20 center construction provides for an increased width of wheel-bearing.

To these ends my invention consists in the novel construction, arrangement, and combination of parts hereinafter described, and 25 pointed out in the appended claims.

Referring to the accompanying drawings, Figure 1 is a plan view of my improved frog. Fig. 2 is a section on the line xx of Fig. 1, and Fig. 3 is a section on the line yy of Fig. 1.

30 A and B designate two continuous T-wing rails bent as shown.

C is a guard-rail, and D is the cast chuck.

Cut in the head of the rail B are two wheel-grooves ff' , whose edges aline, respectively, 35 with the inner lines of the head of the wing portions of the rail A and with the inner line of the head of the guard-rail C. These two grooves leave between them a triangular center or apex portion d of the rail B, whose outer 40 straight face is planed and fitted to the inner planed face a of the central straight portion of the rail A, the base-flanges of the rail B fitting or overlapping the inner base-flange of the rail A at the center of the frog and overlapped upon the opposite side by the inner base-flange of the guard-rail C, which is bent to conform to the angle of the rail B, and has a broadened central head portion c opposite the portion b , the groove intersection being formed 45 in part in the head of the rail B and in part in the head of the guard-rail, as seen in Fig.

2. The guard-rail has apertures c' through its web portions, through which extend the connecting portions of the cast chuck, which fills the space between the webs of the several rails and underlies and supports their heads, forming a solid floor for the frog. This chuck also extends between the rails A and B to each side of the center of the frog to points preferably about coincident with the ends of the guard-rail, floor-plates F being provided to form the bottoms and guard-walls of the wheel-groove. These plates are fitted to the webs of the rails A, as shown in Fig. 3, and extend, respectively, from the grooves ff' to the ends of the chuck D. They are formed with inclines or risers (indicated at f^2) for the purpose of raising the wheel-flanges in passing over the frog. Similar inclines or rising surfaces f^3 are provided in the wheel-grooves of the guard-rail. The several rails, together with the floor-plates, are further united by bolts H, which extend through the rails and through holes cored in the chuck-casting.

75 It will be readily seen that the construction described reduces to a minimum the number of parts and provides a rigid and durable structure.

The formation of the rails A and B at their central portions with the triangular-head portion b abutting the head of the rail A provides, it will be seen, a considerably-increased width of wheel-bearing and makes a neat frog center construction.

80 I do not desire to limit myself to the exact construction which I have described, as the same may be varied in detail without departing from the spirit and scope of my invention.

Having thus described my invention, what I claim, and desire to protect by Letters Patent, is—

1. The herein-described railway-frog composed of the two wing-rails having each a straight intermediate portion abutting a similar portion of the other rail, one of said rails having both wheel-grooves formed across its head, a guard-rail bent to conform to the grooved wing-rail, and having head-grooves which aline with the grooves in the wing-rail, and means for securing said rails together.

2. The herein-described railway-frog com-

posed of two wing-rails having abutted straight portions intermediate their wings, one of said rails having both wheel-grooves formed across its head, a bent guard-rail having head-
5 grooves which align with respective grooves at the wing-rail, a cast-metal chuck, and movable bolts extending through the said rails and chuck.

3. A railway-frog composed of two wing-
10 rails, having each a straight portion intermediate its two wings, one of said rails having both wheel-grooves formed in its head and intersecting across its straight central portion, the latter having the head portion intermediate
15 said grooves formed with a straight face which abuts the similar face of the intermediate portion of the other rail, the bent guard-rail, the cast chuck filling the spaces between the wing and guard rails and cast through the
20 perforations of one of the wing-rails, and the bolts extending through the rail-webs and cast chuck.

4. The herein-described railway-frog comprising the bent wing-rails A and B, having laterally-abutted intermediate portions, one 25 of which has both wheel-grooves of the frog cut across its head, the bent guard-rail, the cast chuck, and the floor-plates between said chuck and the rail A.

5. The herein-described railway-frog comprising the laterally-abutted main rails, one of which has both the wheel-grooves intersecting across the head, the bent guard-rail having the risers, the intermediate cast chuck, and the floor and guard plates intermediate 35 the chuck and the wing portions of the main rail on the opposite side from the guard-rail.

In testimony whereof I have affixed my signature in presence of two witnesses.

CARL F. KRESS, JR.
